PROCESS OF PRODUCING A PURIFIED
PROTECTIVE ATMOSPHERE

James H. Germany, Pittsburgh, Pa., assignor to
Westinghouse Electric & Manufacturing Com-
pany, East Pittsburgh, Pa., a corporation of
Pennsylvania

Application October 20, 1939, Serial No. 300,379

2 Claims. (Cl. 252—372)

This invention relates to a process of pro-
ducing a purified protective atmosphere of hy-
drocarbon gas.

Protective gases are widely used in the heat
treatment of steels. In the bright annealing of
stainless steel and the heat treatment of silicon
steel and high carbon alloy steel, it is desired to
have a very pure protective atmosphere to pre-
vent contamination of the surfaces of the steel
or a change in the alloy composition of the steel
itself.

Pure nitrogen, free from all traces of oxygen,
or a pure nitrogen-hydrogen mixture free from
oxygen, are known to be suitable for use in the
heat treatment of the steels referred to herein-
before. It has been found to be quite difficult to
produce such gases free from oxygen or where
such gases have been produced that the cost of
producing them renders them commercially pro-
hibitive. Heretofore nitrogen gas has been pro-
duced from natural gas by adjusting the gas and
air ratio to produce nitrogen with a small amount
of carbon monoxide and hydrogen while avoid-
ing complete combustion which, with normal var-
iation in the apparatus employed, would cause free
oxygen to be brought over with the processed gas.
Such processed gas is unsatisfactory unless the
impurities are completely removed therefrom,
the removal of the impurities being quite difficult.

An object of this invention is to provide a
process of producing a protective atmosphere
free from impurities from hydrocarbon gas, the
protective atmosphere being suitable for the
bright heat treatment of stainless steel, silicon
steel and high carbon alloy steel.

A more specific object of this invention is to
provide a process of producing a protective at-
mosphere from hydrocarbon gas, such as natural
or manufactured gas, by effecting a complete
combustion of the gas with air, combining the
free oxygen of the combustion products with hy-
drogen and removing the impurities of the com-
bustion products to give the purified protective
atmosphere.

Other objects of this invention will become ap-
parent from the following description when taken
in conjunction with the accompanying drawing,
the single figure of which is a diagrammatic
sketch of apparatus employed in practicing the
process of this invention.

In practicing this invention, a hydrocarbon
gas, such as city or natural gas, is employed in
producing the protective atmosphere. The nat-
ural gas is preferred because it is comparatively
inexpensive as compared to other hydrocarbon

gases and is available in most industrial centers
of the country.

Referring to the drawing, the hydrocarbon gas
is delivered to a pump 10 from any suitable
5 source of supply (not shown) and is mixed in
the pump with air in a predetermined amount.
The air is admitted to the pump 10 and mixed
with the hydrocarbon gas therein in an amount
slightly in excess of the amount necessary for ob-
10 taining a complete combustion of the hydrocar-
bon gas, as will be explained more fully here-
inafter.

When the air and gas are mixed as desired, the
mixture is delivered from the pump 10 to any
15 suitable combustion unit 12, where it is burned to
effect a complete combustion of the mixture. In
burning the mixture in the combustion unit, it
is normally so completely converted that the end
product is produced containing only carbon di-
20 oxide, water vapor and free oxygen, as impurities.
In practicing this process, the presence of only
these three impurities is assured by employing
the excess of air in the mixture, thereby obtain-
ing complete combustion and preventing the for-
25 mation of carbon monoxide.

In order to efficiently remove the impurities
from the end product, it has been found desirable
30 to bleed pure hydrogen or anhydrous ammonia
directly into the combustion unit from any suit-
able source of supply, such as represented at 14.
Where ammonia is employed, it is completely
dissociated into its nitrogen and hydrogen com-
ponents in the heated combustion unit.

It is preferred that the ammonia be admitted
35 to the combustion unit near the end thereof from
which the combustion products are withdrawn,
it being found that the dissociation of the am-
monia is more readily effected due to the high
heat at this portion of the combustion unit. As
40 the ammonia is dissociated, producing the nitro-
gen and hydrogen components thereof, the hy-
drogen of the dissociated ammonia so combines
with the free oxygen present as an impurity in
the combustion products to form water vapor,
45 that as the combustion products leave the com-
bustion unit 12, they comprise the end products
and only carbon dioxide and water vapor as im-
purities. Where pure hydrogen is employed in
place of the anhydrous ammonia, the combining
50 of the hydrogen with the free oxygen is efficient-
ly effected in the heated combustion unit.

In order that the combustion products can
be efficiently treated to remove the impurities
therefrom, the gases are passed immediately
55 from the combustion unit 12 to any suitable con-

denser unit 15, where the water vapor of combustion is condensed to a dew point corresponding to room temperature conditions. With the water vapor at this dew point, it is found that the carbon dioxide and water vapor can be more efficiently removed from the end product of the combustion.

In order to remove the carbon dioxide from the combustion products, they are passed directly from the condenser unit 15 to any suitable carbon dioxide removal system, as indicated at 16, where the last traces of carbon dioxide are efficiently removed from the gases. Any of the commercially known carbon dioxide absorbing materials can be employed in the system 16 for removing this impurity.

In order to remove the water vapor from the combustion products, the gases which have been freed of free oxygen and carbon dioxide are delivered directly to a suitable drier 18 where the last traces of the water vapor which has a dew point corresponding to room temperature conditions, are removed from the end product. In practice, it is found that activated alumina, silica gel and Kieselguhr are suitable for use in the drier for removing the water vapor from the end product. Thus, as the end product leaves the drier chamber 18, only the purified protective atmosphere consisting of nitrogen or nitrogen and hydrogen remains.

In introducing the ammonia into the combustion unit 12 to convert the free oxygen to water vapor, it is generally desired to supply only enough ammonia to the combustion unit to form sufficient hydrogen for combining with all of the free oxygen present in the combustion products to form the water vapor. By controlling and so limiting the amount of ammonia supplied to the combustion unit in this manner, it is possible to produce a protective atmosphere of pure nitrogen. However, where the presence of hydrogen is not undesirable, an excess of ammonia can be introduced into the combustion unit, any excess hydrogen of the dissociated ammonia being carried through the systems described and delivered from the drier to give a protective atmosphere composed of nitrogen with small amounts of hydrogen. As explained hereinbefore, pure hydrogen can be employed interchangeably in place of the anhydrous ammonia.

By practicing the process of this invention, an extremely pure protective atmosphere is produced utilizing a minimum amount of equipment, it being quite evident that by reason of the excess of air employed in effecting the combustion only those impurities which can readily be removed from the combustion products are produced. By introducing the hydrogen component selected from the group consisting of pure hydrogen and anhydrous ammonia directly into the combustion unit, the apparatus is greatly simplified, thereby eliminating any necessity for additional apparatus or causing the dissociation of the ammonia or for additionally heating the combustion productions to cause the desired combining of the introduced hydrogen with the free oxygen to form the water vapor. The protective

atmosphere produced in accordance with the process of this invention is comparatively inexpensive as compared to the cost of the protective atmospheres produced by known processes.

5 Although this invention has been described with reference to a particular process, it is, of course, understood that certain changes may be made therein, and this invention, therefore, should not be restricted except in accordance with the description hereof and the appended claims.

I claim as my invention:

1. The process of producing a purified protective atmosphere from hydrocarbon gases comprising the steps of, mixing the hydrocarbon gas with a predetermined amount of air, introducing the mixture into a combustion unit where it is completely combusted to form the end product containing only carbon dioxide, water vapor and oxygen as impurities, introducing a hydrogen component selected from the group consisting of pure hydrogen and anhydrous ammonia directly into the combustion chamber at a point within the chamber remote from the introduced uncombusted mixture of hydrocarbon gas and air where the hydrogen of the introduced hydrogen component combines with all of the free oxygen to form water vapor, cooling the end products to condense the water vapor to a dew point corresponding to room temperature conditions, passing the end products containing the carbon dioxide and water vapor through a carbon dioxide removal system to remove the carbon dioxide, and drying the water vapor having a dew point corresponding to room temperature conditions from the gas to give a purified protective atmosphere.

2. The process of producing a purified protective atmosphere from hydrocarbon gases comprising the steps of, mixing the hydrocarbon gas with a predetermined amount of air, introducing the mixture into a combustion unit where it is completely combusted to form the end product containing only carbon dioxide, water vapor and oxygen as impurities, the air in the mixture which is combusted being slightly in excess of the amount necessary for obtaining the complete combustion, introducing anhydrous ammonia directly into the combustion chamber at a point within the chamber remote from the introduced uncombusted mixture of hydrocarbon gas and air where it is dissociated into its nitrogen and hydrogen components, the hydrogen of the dissociated ammonia combining with all of the free oxygen to form water vapor, cooling the end products to condense the water vapor to a dew point corresponding to room temperature conditions, passing the end products containing the carbon dioxide and water vapor through a carbon dioxide removal system to remove the carbon dioxide, and drying the water vapor having a dew point corresponding to room temperature conditions from the gas to give a purified protective atmosphere.

JAMES H. GERMANY.
